UNITED STATES PATENT OFFICE.

GILBERT W. GOODRIDGE, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

LAMP-GRIP.

1,187,301.

Specification of Letters Patent. Patented June 13, 1916.

Application filed August 10, 1914. Serial No. 856,085.

To all whom it may concern:

Be it known that I, GILBERT W. GOODRIDGE, a citizen of the United States of America, and residing at Bridgeport, in the county of Fairfield and State of Connecticut, have invented a certain new and useful Improvement in Lamp-Grips, of which the following is a specification.

My invention relates to lamp grips and particularly to a device designed to prevent a lamp from "backing out" of a receptacle of the Edison type under the influence of vibration and the outwardly wedging action caused by the pressure exerted upon the 15 more or less cone shaped lamp base, after it has been screwed home in the receptacle.

In the accompanying drawings, Figure 1 is a broken elevation of a lamp socket to which my invention is applied in one form; Fig. 2 is a broken elevation of the screw shell taken at right angles to the position shown in Fig. 1; and Fig. 3 is a plan of the spring ring shown in the preceding figures.

My invention is here shown embodied in a 25 lamp socket, but it is to be understood that it is applicable to lamp receptacles of any type.

The present socket is provided with the usual casing comprising cap 5 and shell 6 enclosing the insulating body 7 of the socket 30 on which the screw shell side contact 8 is mounted in any convenient manner. As is generally understood, the lamp base is screwed into the socket and held by its threaded engagement with the screw shell 35 side contact 8. In order to effect a gripping action upon the inserted lamp base, I have longitudinally slotted the screw shell at a plurality of points 9, so that the free end of the shell is susceptible of constriction 40 under the influence of a suitable spring member. To effect this constriction I have screwed upon the exterior of the shell a ring 10 of spring metal such as tempered steel and of more or less elliptical shape. The 45 long diameter of this ring exceeds, and the short diameter of the ring is less than, the normal diameter of the shell 8. Consequently when the ring is in adjusted position upon the shell, the pressure across the 50 shorter diameter thereof effects a constricting action upon the slotted end of the screw shell 8. The latter is thereby deformed from its normal cylindrical shape by the pressure of the spring ring 10. Upon the insertion 55 of the lamp base, the latter is thus firmly

clamped and held by the spring ring against accidental reverse rotation or "backing out".

To adjust the spring ring 10 in position on the shell 8, it is only necessary to compress the ring upon its longer axis until it 60 assumes a circular shape, whereupon it may be threaded upon the exterior of the screw shell 8. It is of course desirable to position the ring as close to the outer end of the shell as is commensurate with the security of its adjustment, since the pressure 65 thereof upon the segments of the shell is most effective at this point. Where the slots 9 are diametrically opposite, as in the construction illustrated, the short diameter of 70 the ring lies at right angles to the diameter of the shell which passes through the slots 9. Adjusted in this position the free ends of the shell are pressed inward, as shown.

Various modifications of the construction shown will readily suggest themselves and I do not limit my invention to the precise details illustrated.

I claim as my invention:—

1. A lamp receptacle comprising a longitudinally slotted screw shell side contact and spring means engaging a thread of the shell for constricting the free ends of the segmental portions of the shell to effect a gripping action upon an inserted lamp base. 80

2. A lamp receptacle comprising a longitudinally slotted screw shell side contact and a spring ring mounted exteriorly upon the segmental portions of the shell and within the threaded area of the latter to constrict 85 the same, substantially as described.

3. A lamp receptacle comprising a longitudinally slotted screw shell side contact and mounted exteriorly thereon an elliptical spring ring, the short diameter of which is 90 less than the normal diameter of the screw shell.

4. A lamp receptacle comprising a longitudinally slotted screw shell side contact and mounted exteriorly thereon an elliptical 100 spring ring threaded into position on said screw shell and having a short diameter less than the normal diameter of the screw shell.

5. A lamp receptacle having a deformable screw shell and spring means engaging the threaded portion of the shell for constricting the same against the entry of a lamp base, substantially as described. 105

6. A lamp receptacle comprising a longitudinally slotted screw shell side contact and 110

mounted exteriorly thereon an elliptical spring ring, the short diameter of which is less than the normal diameter of the screw shell, said spring ring having an internal thread to facilitate the screwing of said ring into adjusted position on the screw shell while the ring is temporarily deformed into annular shape.

In testimony whereof I have signed my name to this specification, in the presence 10 of two subscribing witnesses.

GILBERT W. GOODRIDGE.
